UNITED STATES PATENT OFFICE.

BERGET H. BLOCKSOM, OF CHICAGO, ILLINOIS, ASSIGNOR TO WILSON & CO., INC., OF CHICAGO, ILLINOIS, A CORPORATION OF NEW YORK.

CUSHION-COVER.

1,349,258.

Specification of Letters Patent. Patented Aug. 10, 1920.

Application filed May 21, 1917. Serial No. 169,810.

To all whom it may concern:

Be it known that I, BERGET H. BLOCKSOM, a citizen of the United States, residing at Chicago, in the county of Cook and State 5 of Illinois, have invented certain new and useful Improvements in Cushion-Covers, of which the following is a specification.

This invention relates to a cover for cushions and has for its object the provision 10 of means whereby the cushion is maintained indefinitely in its original form, thus insuring its continued resiliency. Further objects and advantages of my invention will 15 be apparent as it is better understood by reference to the following specification when read in connection with the accompanying drawing, illustrating the preferred embodiment thereof in which—

Figure 1 is a view in perspective of a 20 cushion embodying my invention.

Fig. 2 is a similar view with one of the flaps turned back.

Fig. 3 is a view in perspective showing 25 the under side of the cushion and the fastening means for the flap, and

Fig. 4 is an enlarged detail in section through one end of the cover.

Referring to the drawing, 5 indicates the 30 filling of the cushion which preferably comprises a pad of interstitched hair cut to a definite size with its edges substantially perpendicular to the top and bottom of the pad.

The cover comprises a bottom 7 with 35 boxed edges 8 stitched thereto and an auxiliary top section 9 stitched to the boxed edges at one end of the cover. The section 9 is comparatively narrow and the top 6, which corresponds in dimensions to the bottom 7 is stitched to the boxed edges up to the section 9, leaving that part of the top 40 which corresponds in size to the section 9 free from the boxed edges. The boxed edge 10 is stitched to the free end of the top 6, and an auxiliary section 11 is stitched to the 45 boxed edge 10. This free end of the top 6, the boxed edge 10 and the auxiliary bottom section 11 constitute a boxed edge flap for inclosing the end of the cushion, when a

filling is arranged in the cover, and providing a complete boxed edge cushion. The slit between the inner edge of the auxiliary top section 9 and the top 6 permits the insertion and removal of the filling and when the boxed edge flap is secured in place by 50 snap fasteners 12 or other suitable fastening means (Figs. 3-4) the filling will be securely held in the cover and a smooth unbroken top surface provided for the cushion. Fastening straps 13 may be attached to the 55 corners of the cover to secure the cushion in any desirable position for use.

The construction of my improved cover as above described is such that the tendency of the pad 5 to flatten during use is effectively overcome. It is to be understood 60 that the cover may be made of any suitable material which does not give or stretch in use, such for example as canvas. The pad 5 is thus held under light compression when 65 the cushion is in use and will therefore retain its original form almost indefinitely. I find that this result is largely due to the peculiar construction embodying the flaps 70 9 and 11 and the auxiliary edge strip 10 and 75 to the mode of securing the flap 11 to the bottom 7.

Various changes may be made in the form, construction and arrangement of the parts 80 without departing from the spirit or scope of the invention or sacrificing any of the material advantages thereof, the form hereinbefore described, being merely a preferred embodiment thereof.

I claim:

A cover for cushion pads comprising a 85 bottom piece, a box edge stitched thereto about the entire edge thereof, an auxiliary top piece having one end and its side edges stitched to said box edge, a main top piece 90 disposed opposite to said auxiliary piece and having one end and portions of both side edges stitched to said box edge, and a cap formed on the free end edge of said main top piece to fit over and about the end of 95 the cover adjacent to said auxiliary piece.

BERGET H. BLOCKSOM.
